(57) **CLAIM**

The ornamental design for a virtual reality display device, as shown and described.

DESCRIPTION

FIG. 1 is a perspective view of a virtual reality display device showing our new design;

FIG. 2 is another perspective view thereof;

FIG. 3 is another perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof; and,

FIG. 9 is a bottom view thereof.

The broken line portions of the virtual reality display device in FIGS. 1-9 represent unclaimed portions of the claimed design and form no part thereof.
